UNITED STATES PATENT OFFICE.

ZENFORD TERRIAN AND JAMES LENNON, JR., OF FORT EDWARD, NEW YORK; SAID JAMES LENNON, JR., ASSIGNOR TO JAMES LENNON, SR., OF FORT EDWARD, NEW YORK.

PAPER AND PULP SCREEN.

1,115,035.

Specification of Letters Patent. Patented Oct. 27, 1914.

Application filed January 10, 1914. Serial No. 811,421.

To all whom it may concern:

Be it known that we, ZENFORD TERRIAN and JAMES LENNON, Jr., citizens of the United States, residing at Fort Edward, in 5 the county of Washington and State of New York, have invented certain new and useful Improvements in Paper and Pulp Screens, of which the following is a specification, reference being had to the accompanying 10 drawings.

This invention relates to certain improvements in paper and pulp screens and has 15 relation more particularly to a device of this general character wherein suction is employed to draw the pulp through the screen plates; and the object of the invention is to provide a device of this general character having novel and improved means 20 for creating the requisite suction action and wherein such means is positioned to one side of the plates.

The invention consists in the details of construction and in the combination and arrangement of the several parts of our 25 proved device whereby certain important advantages are attained and the device is rendered simpler, less expensive and otherwise more convenient and advantageous for use, all as will be hereinafter more fully set 30 forth.

The novel features of the invention will be carefully set forth in the appended claims.

In order that our invention may be the better understood, we will now proceed to 35 describe the same with reference to the accompanying drawings, wherein—

Figure 1 is a view in top plan with parts in section of a screen constructed in accordance with an embodiment of our invention. 40 Fig. 2 is a view in front elevation with parts in section of the device as embodied in Fig. 1. Fig. 3 is a view in end elevation of the device as herein disclosed. Fig. 4 is a fragmentary sectional view taken through one 45 of the cylinders herein disclosed and its concomitant parts. Fig. 5 is a horizontal sectional view taken through adjacent cylinders, as herein disclosed. Fig. 6 is a fragmentary view in elevation illustrating in 50 detail the screen plates herein disclosed.

As disclosed in the accompanying drawings, 1 denotes a suitably supported vat provided with a plurality of partitions 2 whereby the chambers 3 are afforded, such 55 partitions being of predetermined height

and the chambers thus created are inclosed, in any suitable manner, by the screen plates 4. Suitably supported adjacent one side of the vat 1 are the cylinders 5, herein shown as disposed in substantial continuity, each of such cylinders being of such a length as to intersect the ends of two adjacent compartments 3 and being in communication with such compartments, as indicated at 6. Extending through each of the cylinders 5 is 60 the common rod 7 adapted for sliding or reciprocal movement therethrough and having one end projected beyond an outermost cylinder 5 whereby a suitable operating means may be affixed, such means being 65 herein shown as a belt or band wheel 8 adapted to be coupled, in the usual manner, with any source of supply. Fixed to the rod 7 within each of the cylinders 5 and at a point intermediate the communicating 70 ports 6 is a disk 9 which upon recurrent or reciprocal movement being imparted to the rod 7 is adapted to result in the requisite suction action within the adjacent chambers 3, for purposes which are believed to be 75 clearly apparent to those skilled in the art to which our present invention appertains.

In order to impart the requisite reciprocation or recurrent endwise movement to the rod 7, we herein disclose affixed to the 80 projected portion of such rod the cam disk 10 adapted to travel through the guide-way 11 afforded by the spaced blocks 12, such blocks being herein shown as suitably affixed to the annular band 14 suitably secured to 85 the adjacent end of the vat 1. By this arrangement, it will be observed that as the rod 7 is rotated, the formation of the cam disk 10 is such as to result in reciprocation 90 of the rod and it is thought to be obvious 95 that the extent of reciprocation of the rod can be regulated by varying the pitch of the cam disk.

From the foregoing description, it will be obvious that a paper and pulp screen constructed in accordance with our invention is of an extremely simple and comparatively inexpensive nature and is particularly well adapted for use by reason of the convenience and facility with which it may be assembled and of the effectiveness with which it performs its requisite functions and it will also be obvious that our invention is susceptible of some change and modification without material departure from the prin- 100 105 110

ciples and spirit thereof and for this reason we do not wish to be understood as limiting ourselves to the precise arrangement and formation of the several parts herein shown in carrying out our invention in practice.

Having thus fully described our invention what we desire to claim and secure by Letters Patent, is:

1. The combination with a vat provided with a plurality of chambers, and screen plates for covering such chambers; of a cylinder common to adjacent chambers and in communication therewith through suitable ports produced in the adjacent wall of the vat, a rod common to all the cylinders and directed therethrough and capable of reciprocal movement, a disk fixed to such rod within each of the cylinders intermediate the points of communication of such cylinder with the adjacent series of chambers, and means for imparting reciprocal movement to the rod.

2. The combination with a vat provided

with a plurality of chambers, and screen plates for covering such chambers, such chambers being arranged in a series of two; of a cylinder common to each series of chambers and in communication therewith through suitable ports produced in the adjacent wall of the vat, a rod common to all the cylinders and directed therethrough and capable of reciprocal movement, a disk fixed to such rod within each of the cylinders intermediate the points of communication of such cylinder with the adjacent series of chambers, and means for imparting reciprocal movement to the rod.

In testimony whereof we hereunto affix our signatures in the presence of two witnesses.

ZENFORD TERRIAN.
JAMES LENNON, JR.
